MATERIAL REDUCING ROTOR

Bernard H. Landenberger, Columbus, Ohio, assignor to The Jeffrey Manufacturing Company, a corporation of Ohio

Application May 31, 1946, Serial No. 673,501

3 Claims. (Cl. 241—192)

1

My invention relates to material reducing apparatus and more particularly to a material reducing rotor assembly which includes rotatable reversible material reducing elements.

An important object of my invention is to provide an improved material reducing rotor having hammers or material reducing elements of a rigid or semi-rigid type wherein the material reducing elements include a plurality of surfaces, legs or extending members, the hammers or material reducing elements being positionable upon said rotor whereby the surfaces, legs or extending members may be selectively employed as working elements for reducing material.

Another important object of my invention is to provide improved means for securing and positioning hammer or material reducing elements to material reducing rotors whereby the positions of the material reducing elements may be changed with respect to the rotor.

In carrying out the foregoing object it is a further object of my invention to provide a material reducing rotor element having improved means for securing the hammer or material reducing elements thereto, the means for securing the material reducing elements including spaced means adapted to interfit the hammer or material reducing elements with the rotor, said spaced means preferably being arranged symmetrically whereby the positions of the material reducing elements may be selectively changed with respect to the rotor to permit rotation of the reducing elements to different positions thereby permitting different portions of the material reducing elements to function as the material reducing means thereof.

Another object of my invention is to provide a material reducing rotor which carries a plurality of removable hammers or material reducing elements of the rigid or semi-rigid type wherein the working forces exerted during operation of the rotor by the material reducing elements are transferred directly to the rotor body.

It is yet another object of my invention to provide improved rotor and material reducing element construction wherein the rotor and material reducing element are secured together by spaced means engaging the side surfaces of the material reducing element whereby working loads of the material reducing element are transferred directly to the rotor through the spaced means.

Other objects of the invention will appear hereinafter the novel features and combinations being set forth in the appended claims.

In the accompanying drawings,

2

Fig. 1 is a vertical section of a rotary reducing machine embodying my invention;

Fig. 2 is a fragmentary view in elevation of the rotor shown in Fig. 1, a portion thereof being removed to show features of its construction more clearly;

Fig. 3 is a view in perspective of a fragment of a plate or disc member of the rotor shown in Figs. 1 and 2 and showing a preferred form of my improved mounting means for securing a material reducing hammer thereto; and

Fig. 4 is a view in perspective showing a preferred form of hammer or material reducing element which is adapted to be received by the improved mounting means shown in detail in Fig. 3.

Referring to the drawings and first to Fig. 1 thereof, the reference numeral 10 designates generally a suitable form of material reducing casing or housing and the numeral 11 a rotor body or assembly of suitable construction which is to be described in detail hereinafter.

Since the illustrated casing is well known in the art and is shown and described in United States Patent No. 2,045,689, dated June 30, 1936, to Walter J. Armstrong, and the patents therein referred to, a particular description of the casing or housing 10 is unnecessary here.

The rotor assembly 11 includes a number of center discs or plate members 12 and a pair of end discs or plate members 13 keyed on a shaft 14. The shaft 14 is revolvable in suitable bearings of the housing 10, which are not shown. The discs or plates 12 and 13 are axially spaced on the shaft 14 by means of spacer collars 15 keyed with the discs to the shaft 14 by a key 16. The discs or plates 12 and 13 are provided with a number of apertures 17 (see Fig. 3) all of which preferably have their centers on the circumference of a common circle concentric with the shaft 14. The apertures 17 receive rods or pins 18 which extend through all of the discs 12 and 13. The ends of the rods or pins 18 are threaded and are provided with nuts 19. The construction of the rotor thus far described may be identical to that of the rotor described in Patent 2,045,689, above mentioned.

Each of the discs or plates 12 and 13 of the rotor body or assembly 11 is provided with spaced sets of clustered hammer holders in the form of spaced blocks or shoulder forming members 20 that form a plurality of substantially identical abutments which serve for securing hammer or material reducing elements 21 to the discs or plates 12 and 13 and these sets of spaced blocks are clustered about every other one of the apertures 17 in the plates 12 and the left-hand end

plate 13 of the rotor as seen in Fig. 2. These blocks are preferably, but not necessarily, secured permanently to the discs or plates as by molding them integral therewith or by welding them thereto. As shown in the drawings, each of the discs or plates 12 and 13 is provided with six of the apertures 17 which are equally spaced therein, and, with the exception of the right hand disc 13, every other one of the apertures in each disc has clustered about it in spaced relation a set of hammer holding blocks 20.

The apertures 17 are formed in the discs or plates 12 and 13 so that when the discs or plates are secured and keyed to the shaft 14 the apertures 17 will be in alignment for receiving the rods or pins 18. Preferably the sets of spaced blocks or fastening members 20 of each plate are arranged in staggered relation with the spaced sets of hammer holding blocks or fastening members 20 of the adjacent plates or discs, as seen in Fig. 2, but it will be obvious that any desired arrangement of the sets of hammer holders 20 of one disc or plate with respect to those of the other discs or plates may be had.

In Fig. 4 a preferred form of hammer or material reducing element 21 is shown. This element is generally flat and includes a central opening 22 from about which extend radially three legs or projections 23. The projections or legs 23 are spaced equally and the sides thereof form material reducing hammer surfaces 24 that are formed to provide sharp cutting edges 25 where they intersect the end surfaces 26 of each leg or projection 23. Each hammer element 21 is adapted to fit slidably sidewardly or axially into the spaces between the blocks 20 of each set thereof and is received or embraced about its hub or base, the blocks 20 extending in the spaces 27 between the legs 23 of the hammer elements. The blocks 20 are so shaped and spaced with respect to the aperture 17 about which they are clustered and with respect to the contour of the reducing element 21 that the projections, legs, or shoulder elements 23 thereof extend between the blocks 20 and the surfaces 24 thereof engage the shoulder or side surfaces of the blocks. The blocks 20 retain the elements 21 in such position that the aperture 17 of the discs or plates and the apertures or central openings 22 of the material reducing element 21 are in alignment and may freely receive a rod or pin 18.

The hammer elements 21 are mounted between the blocks 20 of each of the sets thereof and one side of each hammer element abuts the disc 12 or 13 to which the blocks are secured. The material reducing hammer elements 21 are retained against sideward or axial movement in the opposite direction or away from the discs which they abut, which movement would result in their disengagement from the blocks 20, by spacer collars 28 which are secured between the elements 21 and the adjacent discs or plates 12 and 13. The rods or pins 18 extend through the aligned apertures 17 in the discs 12 and 13, through the collars 28 and the openings 22 in the elements 21 and are secured therein by the nuts 19.

It will be obvious that one leg 23 of each of the hammer elements 21 projects radially beyond the peripheries of the discs while the other legs 23 thereof are within the peripheries thereof. As a consequence of this arrangement only that leg of the hammer element which projects beyond the peripheries of the discs will function as a working leg. It will also be seen that the functions of the rods or pins 18 is to tie the plates or discs

12 and 13 together and to retain the spacer collars 28 in position. The hammer elements 21 are retained or secured to the rotor body against both inward and outward radial movement and against rotation about their own centers by the spaced sets of spaced blocks 20 which may closely interfit the irregularities in the shape or contour of the material reducing elements 21. In each cluster of three holding blocks 20 there are two adjacent each hammer element 21, one on each side thereof, which are peripherally spaced apart and are radially outside the inwardly extending legs of said element 21, thus locking it against radially outward movement. The third block 20 is 10 radially inward of the two outer blocks 20 and is between said inwardly extending legs, thus locking said element 21 against radial inward movement. All three blocks 20 obviously lock each element 21 against rotary movement about 15 its center. The rods or pins 18 do not carry the hammer elements, but the holding blocks 20 do and therefore the rods or pins are not subjected to shear loads by the hammers. The shear loads of the hammers are transferred directly to the discs through the blocks 20.

When the rotor 11 is in operation, the centrifugal force of the hammer elements 21 causes them to tend to center themselves between the outer pair of the spaced blocks 20. Because of 30 the relatively small inclines of the angles between the innermost surfaces of the outer blocks, that is, the included angle between them, the elements will not become locked to the discs or plates 12 and 13, although in certain instances 35 it may be desirable to make the included angle more acute so that such action will occur.

The construction and arrangement of the mechanism hereinbefore described which permits reversing and shifting of the positions of the 40 material reducing hammer elements 21 with respect to the rotor 11 is an important feature of my invention. The means for accomplishing this reversibility and shiftability is, namely, the spaced sets of spaced hammer holding blocks, shoulder or abutment forming means 20, and the arrangement thereof in which they preferably extend between adjacent pairs of discs or plates 12 and 13. With the arrangement described, the hammer elements 21 may be removed and reversed, that is, the sides thereof 45 adjacent the plates 12 or 13 may be made to face the side of the next adjacent plate by removing the rods or pins 18, the spacer collars 28, and by removing the element 21 by sliding it from its holding blocks and turning it side for side and replacing it between its set of spaced blocks 20 and then replacing the spacer collars and pins. Because the elements 21 are symmetrical, they may each be removed from 50 between their holding blocks 20 and rotated upon the axis of their central opening and then be replaced between their holding blocks to present a new material reducing surface or leg which extends beyond the periphery of the discs or plates 12 or 13. This is particularly advantageous since in operation the leading or sharp cutting edges 25 as well as the surfaces 24 and 55 26 that are functioning as the working surfaces and edges of the hammers 21 may become worn and they may be renewed simply by removing the hammer elements from their holding blocks 20 and by rotating each of the elements upon its axis through 120 degrees and replacing and locking them within their holders. When one 60 edge 25 has been worn from each of the legs 23

the material reducing elements may be reversed or turned around, as was previously described, to present the edges 25 of the legs which were formerly the trailing edge of the element, and consequently were unworn, to cause them to become the leading or working edges. Upon wearing away of the newly presented cutting edge of any one or all of the elements, each again may be rotated upon its axis as described to bring the unworn edge of another of the legs into working or material reducing position. It will be obvious, however, that in a material reducing apparatus wherein the rotors are reversible, that is, wherein the rotors may rotate first in one direction and then their direction of rotation may be reversed, both of the cutting edges 25 of each leg which is functioning as a working leg may be worn away. In such case both of said edges of each hammer may be renewed by merely removing each hammer element 21 from between its holding blocks 20 and rotating it through 120 degrees upon its axis and replacing it within its holding blocks.

While I have shown a preferred element 21 as including three legs 23, it will be understood that an element having more or less legs than the element shown may be used and in certain instances may be more desirable than the element which I have shown. It will, of course, be understood that should the outer contour of the element 21 be changed by adding or subtracting projections or legs, the shape or arrangement or both of the sets of spaced blocks or members 20 will be changed accordingly.

Referring again to Fig. 1, the apparatus shown there includes my improved apparatus rotor and in the operation of this device lumps of material to be reduced are fed into the apparatus through a feed opening 29 in the top thereof and the lumps of material fall into a material reducing chamber 30, or what is known in the art as a "torture chamber." As seen in Fig. 1 the material reducing chamber or "torture chamber" is above the rotor assembly 11. In the embodiment of the material reducing apparatus shown, the rotor assembly 11 rotates counterclockwise and the hammer or material reducing elements 21 thereof strike the lumps of material falling into the chamber 30 and fracture, cut and/or knock them against the left side of the chamber 30 and against breaker or liner plates 31 thereof, thereby further reducing them. The lower liner plate 31 includes an inwardly projecting portion 32 which extends transversely of the chamber 30 and closely adjacent the peripheral path of the material reducing hammers 21 which cooperate therewith to grind or pulverize the material. Thus the portion 32 forms a grinding element, surface or bar which extends entirely across the bottom of the chamber 30.

As material which is being reduced falls or otherwise comes between the edges 25 of the hammers 21 and an edge 33 of the portion 32 of the lower liner plate 30, it is cut, crushed, or otherwise fractured, to reduce the size of the particles so that they may pass through spaces 34 between the rotor 11 and the lower liner plate 31. Material which passes through the space 34 will fall or be knocked downwardly upon a two piece screen 35 which encases the lower half of the rotor assembly 11. Thus particles which have been sufficiently reduced in size will pass between the bars of the screen 35 and will be discharged through the open bottom of the casing or housing 10 as the finished product of the re-

ducing apparatus. The particles of material which pass through the space 34 but which have not been sufficiently reduced to permit them to pass between the bars of the screen 35 will be carried over the screen by the reducing hammers 21 and returned to the reducing chamber 30 where they will again be submitted to the material reducing actions taking place therein.

With my improved apparatus rotor the rotational force of the hammer elements 21 upon their axes created by their striking and grinding the lumps of material, as well as the centrifugal force developed by them, are transferred directly to the discs 12 and 13 of the rotor assembly through the blocks 20 of the sets thereof which form the hammer holding elements. It is to be particularly noted that the rods or pins 18 do not functionally connect the material reducing or hammer elements 21 with the discs 12 and 13 and that therefore the elements 21 impart no shear loads to the rods or pins. As previously mentioned, the rods or pins 18 function to retain the spacer elements 28 in position and to tie the discs 12 and 13 together.

From the foregoing it will be obvious that I have provided an improved material reducing apparatus wherein the material reducing elements may be of the rigid or semi-rigid type and wherein the working forces exerted by them are transmitted directly to the discs 12 and 13 through the blocks 20 which form parts thereof. It will be seen, however, that the blocks 20 need not form integral parts of the discs 12 and 13 but may be removably secured thereto as by means of bolts, rivets or the like.

Obviously those skilled in the art may make various changes in the details and arrangement of parts without departing from the spirit and scope of the invention as defined by the claims hereto appended and I wish therefore not to be restricted to the precise construction herein disclosed.

Having thus described and shown an embodiment of my invention, what I desire to secure by Letters Patent of the United States is:

1. A rotor including a shaft, a plurality of spaced discs carried and driven by said shaft, a plurality of removable material reducing hammer elements each having at least three legs wherein different legs of said hammer elements may be positioned to extend radially outward beyond said discs thereby to function as working elements for reducing material, said rotor being adapted for use in a material reducing apparatus, said material reducing hammers being between said discs, each hammer including at least three spaced legs extending radially from a central axis, one of said legs extending radially outwardly beyond said discs, other of said legs extending inwardly of the peripheries of said discs, spaced sets of spaced blocks secured to the discs, each set including two blocks adjacent the periphery of a disc and on opposite sides of the outwardly extending hammer element leg and radially outwardly of said inwardly extending legs, an inner block positioned between said inwardly extending legs, all said blocks being adapted to receive interfittingly one of said material reducing hammer elements, and means retaining said hammer elements against axial movement relative to said blocks, whereby said sets of blocks retain said material reducing hammer elements against both radial inward and radially outward movement relative to said discs and against rotational movement upon their axes.

2. A rotor including a shaft, a plurality of spaced discs carried and driven by said shaft, a plurality of removable material reducing hammer elements each having at least three legs wherein different legs of said hammer elements may be positioned to extend radially outward beyond said discs thereby to function as working elements for reducing material, said rotor being adapted for use in a material reducing apparatus, said material reducing hammers being between said discs, each hammer including at least three spaced legs extending radially from a central axis, one of said legs extending radially outwardly beyond said discs, other of said legs extending inwardly of the peripheries of said discs, spaced sets of spaced blocks secured to the discs, each set including two blocks adjacent the periphery of a disc and on opposite sides of the outwardly extending hammer element leg and radially outwardly of said inwardly extending legs, at least one inner block positioned radially inwardly of said disc periphery and radially inwardly of some of said other legs which extend inwardly of the peripheries of said discs, all said blocks being adapted to receive interfittingly one of said material reducing hammer elements, and means retaining said hammer elements against axial movement relative to said blocks, whereby said sets of blocks retain said material reducing hammer elements against radially outward movement relative to said discs.

3. A rotor including a shaft, a plurality of spaced discs carried and driven by said shaft, a plurality of removable material reducing hammer elements each having at least three legs wherein different legs of said hammer elements may be positioned to extend radially outward beyond said discs thereby to function as working elements for reducing material, said rotor being adapted for use in a material reducing apparatus, said material reducing hammers being between said discs, each hammer including at least three spaced legs extending radially from a central axis, one of said legs extending radially outwardly beyond said discs, other of said legs extending inwardly of the peripheries of said

discs, spaced sets of spaced blocks secured to the discs, each set including two blocks adjacent the periphery of a disc and on opposite sides of the outwardly extending hammer element leg and radially outwardly of said inwardly extending legs, at least one inner block positioned radially inwardly of said disc periphery and radially inwardly of some of said other legs which extend inwardly of the peripheries of said discs, all said blocks being adapted to receive interfittingly one of said material reducing hammer elements, and means retaining said hammer elements against axial movement relative to said blocks, whereby said sets of blocks retain said material reducing hammer elements against both radial outward and inward movement relative to said discs and against rotational movement upon their axes.
